UNITED STATES PATENT OFFICE.

PETER W. RASMUSSEN, OF CRAWFORD TOWNSHIP, ANTELOPE COUNTY, NEBRASKA.

SASH AND DOOR HOLDER.

1,156,813.

Specification of Letters Patent. Patented Oct. 12, 1915.

Application filed July 3, 1915. Serial No. 38,002.

To all whom it may concern:

Be it known that I, PETER W. RASMUSSEN, a citizen of the United States of America, residing in Crawford Township, in the 5 county of Antelope and State of Nebraska, have invented certain new and useful Improvements in Sash and Door Holders, of which the following is a specification.

The invention relates to a tool or implement designed primarily for carpenter's use 10 and adapted for holding sash, doors, or similar articles on edge while they are being fitted and trimmed.

In implements of this character it is desirable 15 that they support the door or sash in a comparatively rigid manner to permit of convenient working thereon and that they be readily adjustable to accommodate sash or doors of different widths; the capacity 20 of the implement to be folded into a comparatively small compass when not desired for use being a highly desirable additional feature.

It is the object of the present invention 25 to provide a compact foldable implement of this type which may be readily adjustable to accommodate doors or sash of different width and which will rigidly support the door or sash in a manner to permit it to be conveniently 30 worked upon, the parts of the structure readily adapting themselves to be folded and in effect locked in folded relation so as to provide a small compact structure which may be readily and conveniently 35 carried from place to place.

The invention in the preferred form of 40 details will be described in the following specification, reference being had particularly to the accompanying drawings, in which:

Figure 1 is a perspective view illustrating the use of the improved implement; Fig. 2 is a plan of the same showing the parts in folded relation; Fig. 3 is a side elevation of 45 the folded implement.

In the accompanying drawing wherein it will be understood is illustrated the preferred form of detail, the improved implement comprises a base strip 1 of an ap-

propriate length and preferably provided at 50 one end with a felt or fabric pad 2 to permit the implement, as a whole to be braced against any suitable fixture without liability of marring the latter. The base strip 1 is designed to support one end of the door or 55 sash and is of such thickness as will support the article above the floor or other surface to avoid marring or injuring the lower edge.

The supporting structure proper involves 60 a foot piece 3 and a head piece 4, each substantially of U-form including side plates 5 arranged in spaced parallel relation and connected by a cross strip 6, thus forming a U-housing for the edge of the door or sash 65 to be worked. The foot piece 3 has the side 70 plates 5 extended below the cross strip 6 forming ears 7 which are pivotally connected at 8 to the base strip 1, the pivotal connection being such that the foot piece may be swung down upon the base strip when desired, the side plates 5 of the foot piece being spaced apart to bridge the base strip 75 when so turned. The head and foot are connected for relative adjustment vertically through connectors involving telescopic 80 members 9 and 10, the former being preferably threaded into projections 11 extending outwardly from the side plates 5 and the latter suitably fixed in similar projections 12 projecting outwardly from the side plates 85 5 of the head. Member 10 telescopes within member 9 and is held in adjusted relation through the medium of a set screw 13 in an obvious manner. The telescopic supports thus provided, and being one on each side 90 of the head and foot, permit of vertical adjustment of the head with relation to the foot so that the device as a whole may accommodate doors or sash of different width.

A brace or positioning strut is pivotally connected to the edge supporting structure involving the head and foot, said brace or strut comprising telescopic members 14 and 15, the former being pivotally connected at 16 to the base strip adjacent one end thereof and the latter pivotally connected at 17 to the cross bar 6 of the head. The telescopic sections are held in 95

fixed relation through the medium of a set screw 18, as will be obvious from the drawing. Lateral brace strips in the form of legs 20 are pivotally connected to the cross piece 5 of the foot 3, being arranged thereon opposite the projection of the plates 5 of the foot, and the cross piece is undercut or otherwise formed to provide a holding ledge 21 which projects outwardly beyond the face 10 of the cross piece and has its lower edge inclined outwardly and downwardly in both directions from the central point as at 22 so that when the parts are in operative position the lateral brace strips 20 are held in 15 fixed position between the base strip 1 and the ledge 21, the free terminals of the lateral brace strips resting on the appropriate surface and holding the structure as a whole rigidly against lateral movement.

20 In conjunction with the base strip 1 which as compared with the length of the door or sash being operated upon is comparatively short, I provide a block 24 recessed at 25 to receive the lower edge of the 25 sash or door at a point remote from the base strip, the block serving as the opposite end support, as will be obvious.

In operative use as illustrated in Fig. 1, the holding section including the foot and 30 head piece is turned up on the base strip to an approximately vertical position, and through the medium of the telescopic members described the head is adjusted vertically with relation to the foot to properly space the parts. The door or sash is disposed on edge and the end thereof inserted between the plates 5 of the head and foot. In this connection I contemplate the use of 35 a wedge strip 26 arranged between the side of the door or sash and one of the plates 5 of the head to effectively clamp the door or sash against accidental displacement. The positioning or brace strut having been automatically adjusted in this positioning of 45 the supporting section the set screws are tightened to lock the parts in adjusted positions. The door or sash may be then fitted, trimmed, or otherwise worked on as desired, being reversed or supported on supporting edge or held in any edge position desired by an obvious adjustment of the 50 parts.

After use the implement as a whole may be readily collapsed by loosening the set 55 screws 12 and 18 and moving the head toward the foot to the limit of such movement. The supporting member is then turned down onto the base strip 1 on the pivotal supports 8, whereupon the set screws 60 12 and 18 are turned to lock the parts in their folded relation. The lateral brace strips 20 are then turned inwardly to overlie and rest upon the base strip 1, when the implement will be folded into a compara-

tively compact package for convenient 65 storage or transportation.

What is claimed is:

1. A carpenter's implement including a base strip, a supporting member pivotally connected thereto, and comprising approximately U-shaped head and foot members, and telescopic connectors between said members. 70

2. A carpenter's implement including a base strip, a supporting member pivotally 75 connected thereto, and comprising approximately U-shaped head and foot members, and telescopic connectors between said members, and a brace strut involving telescopically connected members, said members being respectively pivoted to the base strip 80 and to the supporting member.

3. A carpenter's implement including a base strip, a supporting member pivotally 85 connected thereto, and comprising approximately U-shaped head and foot members, and telescopic connectors between said members, and lateral brace members pivotally connected to the supporting member.

4. A carpenter's implement including a 90 base strip, a supporting member pivotally connected thereto, and comprising approximately U-shaped head and foot members, and telescopic connectors between said members, and lateral brace members pivotally 95 connected to the supporting member, and means carried by the supporting member for bracing the lateral strips against upward movement.

5. A carpenter's implement including a 100 base strip, a supporting member pivotally connected thereto, and comprising approximately U-shaped head and foot members, and telescopic connectors between said members, and lateral brace members pivotally 105 connected to the supporting member, the foot section of the supporting member having a ledge to overlie and bear upon the lateral brace strips when the latter are positioned for use. 110

6. A carpenter's implement comprising a base strip, a U-shaped foot pivotally connected thereto, lateral brace strips pivotally connected to the foot member, a U-shaped head member, and telescopic rods connecting 115 the head and foot member. 110

7. A carpenter's implement comprising a base strip, a U-shaped foot pivotally connected thereto, lateral brace strips pivotally connected to the foot member, a U-shaped head member, and telescopic rods connecting the head and foot member, a telescopic brace strut pivotally connected to the head member and to the base strip. 120

8. A carpenter's implement comprising a 125 base strip, a U-shaped foot pivotally connected thereto, lateral brace strips pivotally connected to the foot member, a U-shaped

head member, and telescopic rods connecting the head and foot member, a telescopic brace strut pivotally connected to the head member and to the base strip, said supporting member being adapted to be folded down upon the base strip, the base strip locking the supporting member in folded relation.

In testimony whereof I affix my signature in presence of two witnesses.

PETER W. RASMUSSEN.
